DOOR LOCK

William V. Schweitzer, New Britain, Conn., assignor to
The American Hardware Corporation, New Britain,
Conn., a corporation of Connecticut

Application February 3, 1956, Serial No. 563,299

4 Claims. (Cl. 292—224)

This invention relates to a door lock and more particularly to an improved door lock of the so-called "unit" type which is primarily intended for use on "communicating" doors; this term being generally applied to doors between adjoining bedrooms, offices, hotel rooms and the like.

Such locks are generally provided with a turnpiece or a key operated cylinder lock in each knob which is each adapted to operate a separate dogging mechanism for dogging the opposite knob against operation. When a turnpiece is provided in each knob, the occupant of either of two adjoining rooms can selectively prevent entry therein to or from the other of said rooms. With locks having a key operated cylinder lock in each knob, either or both of said knobs can be rendered inoperative only by a person possessing the proper key.

The invention disclosed in this application is embodied in the dogging mechanisms which are operable either by a turnpiece or a cylinder lock to dog the knob shanks of the lock against operation, and has as its primary object the provision of an improved and greatly simplified dogging mechanism for each of said knob shanks which utilizes the rollbacks of the lock for effecting the dogging of the said shanks.

A further object of this invention is to provide a unit lock in which the dogging mechanisms for the knobs thereof consist of identical parts which are constructed in such a manner that they may be used in the opposite knob shanks of the lock in reverse relationship.

Further objects and advantages of this invention will be more clearly understood from the following description and the accompanying drawings in which:

Fig. 1 is a plan view of a unit lock embodying the instant invention illustrated in normal unlocked condition.

Fig. 2 is a plan view of the lock, partly in central horizontal section, further illustrating the construction thereof; a portion of the lock structure being omitted.

Fig. 3 is a front view of said lock, partially in central vertical section on line 3—3 of Fig. 1, again showing the dogging mechanism in normal unlocked condition.

Fig. 4 is a sectional end view of the lock.

Fig. 5 is a view similar to Fig. 2, but showing the dogging mechanism in each of the knob spindles in dogging position.

Fig. 6 is a view similar to Fig. 3, also showing the dogging mechanism in dogging position.

Fig. 7 is a fragmentary plan view of a portion of the lock illustrating the position assumed by the rollbacks thereof when in dogging position.

Fig. 8 is an isometric view illustrating the cam plug and the rollback used in each of the dogging mechanisms of the lock.

The manufacturer of any particular line of door locks generally uses a basic lock housing for each of the locks produced and provides different elements which are insertable into said locks to change the locking functions thereof. The door lock disclosed in this application

utilizes the basic unit lock housing disclosed in my co-pending application Serial No. 498,525, filed April 1, 1955, now Patent No. 2,821,849, and for which the dogging mechanism embodying the instant invention has been designed, but it will readily be understood that said dogging mechanism may be adapted for use in other unit lock housings without departing from the spirit of this invention.

Referring to the drawings, it will be seen that the frame 10 of the unit lock includes an elongated housing 5 having a front wall 6 and rearwardly extending side walls 7—7. A tubular knob shank bearing sleeve 8 extends transversely through the side walls of the housing adjacent the rear end thereof and is secured to said housing by means of pins 9—9 which extend through a tie bar 10 that is fastened to said side walls; this construction being fully disclosed in said co-pending application. The bearing sleeve 8 contains identical diametrically opposed transverse openings 11—11 in the wall thereof that are located centrally with respect to the side walls of the housing, and from the opposite side edges of said transverse openings there extend diametrically opposed locking notches 12—12 and 13—13. A supporting plate 14 is secured to the side walls 7—7 intermediate the ends of the housing and extends transversely thereacross.

The latch bolt 15 of the lock is pivotally mounted to said housing and extends through an opening in the front wall thereof. Said latch bolt is actuated by a conventional retractor 16 including a yoke portion 16-a, which 30 straddles the bearing sleeve 8 and has laterally extending arms 16-b—16-b providing rollback platforms and a bar 16-c which extends forwardly from said yoke portion through an opening in the supporting plate 14 and is pinned to the latch bolt 15 in the conventional manner. 35 The retractor and the latch bolt are biased into normal projected position, as illustrated in Figs. 1 and 4, by a compression spring 17 which surrounds said bar and is disposed between said supporting plate 14 and the latch bolt 15.

40 The knob shank bearing sleeve 8 rotatably supports oppositely disposed, coaxial, tubular knob shanks 18 and 19. The knob shank 18 carries a knob 20 and the knob shank 19 carries a similar knob 21; said knobs being secured to said shanks in the manner fully disclosed in United States Patent No. 2,675,692 of Nicholas A. Welch et al., issued April 20, 1954. The knob shanks are secured against axial movement in the bearing sleeve by suitable retaining rings 22—22, as illustrated in my above mentioned co-pending application, and the adjacent inner ends of said shanks contain diametrically opposed slots 23—23 and 24—24, respectively, which extend into said shanks to a point adjacent the ends of the locking notches 12—12 and 13—13 and are normally aligned therewith. The inner wall of each of said tubular knob shanks 18 and 19 contains a longitudinally extending groove, 25 and 26, respectively, and the outer ends of said shanks have portions thereof cut away providing notches 27 and 28, respectively, therein. It will be noted, particularly in Fig. 2, that each of said knob shanks 18 and 19 is identical in form, but that they are disposed in reverse relationship in the bearing sleeve 8.

45 The knob shanks 18 and 19 carry identical rollbacks 29—29 which are, in most respects, of the conventional unit lock type and, with particular reference to Fig. 8, each of which includes a circular hub portion 30 having opposed radial arms 30-a—30-a extending therefrom. The circular hub portion 30 of each of said rollbacks is slidable within the bore of its respective knob shank and the arms 30-a—30-a extend through the slots therein, the transverse openings 11—11 in the bearing sleeve and over the rollback platforms 16-b—16-b on the retractor. As

in all locks of this type, the spring 17 urges the rollback platforms of the retractor against the sides of the radial arms to retain them in normal centrally disposed position as illustrated in the drawing. The circular hub portion of each of said rollbacks 29-29 contains a hole 30-b therethrough which is located to one side of the axis of said hub portion. Each of the rollbacks is identical in form, but they are carried in their respective knob shanks in reverse relationship so that the holes 30-b-30-b lie on opposite sides of and equidistant from the axis of said knob shanks.

Cylindrical cam plugs 31-31 are slidably contained in the knob shanks 18 and 19 and have tapered outer ends providing cam surfaces 32-32 thereon and pins 33-33 extending radially therefrom into the grooves 25 and 26 in the knob shanks to prevent rotation of said plugs relatively thereto. A pushrod 34 extends from the inner end of each of said cam plugs and is positioned so as to pass through the hole 30-b in the adjacent rollback and into engagement with the hub portion 30 of the rollback in the opposite shank; said pushrods being slidably supported in their adjacent rollbacks.

A cylindrical turnpiece 35 is rotatably supported in each of the knob shanks and extends therefrom through an opening in its respective knob. The inner ends of the turnpieces contain V-shaped notches which receive the ends of the cam plugs 31-31 and provide complementary cam surfaces 36-36 thereon. Each of said turnpieces has a finger engageable portion 35-a at its outer end and is biased inwardly with respect to its knob by a compensating spring 37. Lugs 38-38 extend radially from the turnpieces into the notches 27 and 28 in the knob shanks. Said lugs engage the sides of said notches to limit rotation of the turnpieces to 90 degrees.

A spring 39 is disposed between the cam plug 31 and the rollback 29 in each of the knob shanks, and it will be understood that said springs urge the cam plugs into the notches in the ends of the turnpieces and also urge their respective rollbacks against the free end of the pushrod 34 extending from the opposite shank. It will be noted that the cam plugs and turnpieces are also identically formed, and that they are adapted to be contained within their respective knob shanks in reverse relationship.

The construction of the dogging mechanism above described reduces the cost of manufacture of the lock since the dogging mechanism in each of the knob shanks utilizes the same parts, but carries them in opposed relation, thereby rendering it unnecessary to produce different parts for each of the mechanisms.

The door lock is retained in a slot 40 in the edge of a door 41 by escutcheon plates 42 and 43 which are constructed in the manner fully described in my above mentioned co-pending application.

When the rollbacks 29-29 are in normal unlocked position, as illustrated in Figs. 1 through 4, rotation of the knobs 20 or 21 in either direction will rotate its respective rollback to cause retraction of the retractor and withdrawal of the latch bolt. It will be understood that the turnpiece, cam plug, pushrod and rollback in each shank all turn together and that the end of the pushrod merely slides over the surface of the hub portion of the opposite rollback and revolves around the opposite pushrod.

When it is desired to dog either knob against operation, the turnpiece in the opposite knob is rotated for 90 degrees in a counter-clockwise direction with respect to its knob. Since the turnpiece is retained against outward axial movement by the spring 37 which is stronger than the spring 39, rotation thereof will cam its respective cam plug and pushrod inwardly in the knob shank to slide the opposite rollback relatively to its knob shank into dogging position wherein the radial arms thereon are disposed within the locking notches in the bearing sleeve. Rotation of the opposite knob shank is then prevented, but the knob whose turnpiece was rotated is still free to retract

the latch bolt until dogged in the same manner from the opposite side of the door. In Figs. 5, 6 and 7, I have illustrated the position assumed by the parts of the dogging mechanism when both of said knobs are dogged against operation, but it will be readily understood that either knob may be dogged independently as above described.

The turnpieces may be replaced by suitable key operated cylinder locks and cams of the type disclosed in United States Patent No. 2,694,916 of Frank J. McConnell, issued November 23, 1954, so that either of the knobs may be locked in dogged or undogged condition as desired.

I claim:

1. In a door lock, the combination of a housing having rollback dogging abutments, a retractor movable in said housing, a latch bolt connected to said retractor, a pair of opposed tubular knob shanks mounted to rotate in said housing about a common axis and each having a knob secured to its outer end, a rollback for actuating said retractor non-rotatably connected to the inner end portion of each of said knob shanks and each having a circular hub that is axially slidable in its respective shank, each of said hubs having an opening extending therethrough in an axial direction and said openings being disposed on opposite sides of said common axis, an axially slidable supporting member contained in each of said knob shanks outwardly of and spaced from the rollback therein, a pushrod secured to and extending inwardly from each of said supporting members, said pushrods lying on opposite sides of said common axis and each extending slidably through the opening in the hub of its respective rollback and terminating inwardly of the inner end of its respective knob shank, the free end of each pushrod defining an abutment surface engageable by the hub of the opposite rollback and normally locating said opposite rollback in retractor operating position, a spring contained within each of said knob shanks between the supporting member and the rollback carried thereby for urging the rollback against the free end of the opposite pushrod, each pushrod, upon rotation of its respective knob shank, being carried in a circular path with the free end thereof sliding over the surface of the hub of the opposite rollback while still maintaining said opposite rollback in retractor operating position, and actuating means contained in each knob shank outwardly of the supporting member therein and accessible for manual operation at the outer face of its respective knob, said actuating means being adapted to move its supporting member and pushrod inwardly to thereby shift the rollback in the opposite knob shank axially outwardly and into locking engagement with said abutments on the housing to thereby dog the opposite knob shank against operation.
2. In a door lock, the combination of a housing having rollback dogging abutments, a retractor movable in said housing, a latch bolt connected to said retractor, a pair of opposed tubular knob shanks mounted to rotate in said housing about a common axis and each having a knob secured to its outer end, a rollback for actuating said retractor non-rotatably connected to the inner end portion of each of said knob shanks and each having a circular hub that is axially slidable in its respective shank, each of said hubs having an opening extending therethrough in an axial direction and said openings being disposed on opposite sides of said common axis, an axially slidable cam plug contained within each of said knob shanks outwardly of and spaced from the rollback therein, each of said cam plugs having a cam surface on its outer end, means preventing rotation of said cam plugs relatively to their respective knob shanks, a pushrod secured to and extending inwardly from each of said cam plugs, said pushrods lying on opposite sides of said common axis and each extending slidably through the opening in the hub of its respective rollback and terminating inwardly of the inner end of its respective knob shank, the free end of each pushrod defining an abutment sur-

face engageable by the hub of the opposite rollback and normally locating said opposite rollback in retractor operating position, a spring contained within each of said knob shanks between the cam plug and the rollback carried thereby for urging the rollback against the free end of the opposite pushrod, each pushrod, upon rotation of its respective knob shank, being carried in a circular path with the free end thereof sliding over the surface of the hub of the opposite rollback while still maintaining said opposite rollback in retractor operating position, and a turnpiece rotatably mounted in each of said knob shanks outwardly of the cam plug therein and accessible for manual operation at the outer face of its respective knob, each turnpiece having a cam surface on its inner end cooperating with the cam surface on its respective cam plug whereby, when either of said turnpieces is rotated, it will move its cam plug and pushrod axially inwardly and thereby shift the rollback in the opposite knob shank axially outwardly and into locking engagement with said abutments on the housing to thereby dog the opposite knob shank against operation.

3. In a door lock, the combination of a housing having rollback dogging abutments, a retractor movable in said housing, a latch bolt connected to said retractor, a pair of opposed tubular knob shanks mounted to rotate in said housing about a common axis and each having a knob secured to its outer end, a rollback for actuating said retractor non-rotatably connected to the inner end portion of each of said knob shanks and each having a circular hub that is axially slidable in its respective knob shank, each of said hubs having an opening extending therethrough in an axial direction and said openings being disposed on opposite sides of said common axis,

a longitudinally movable pushrod contained within each of said knob shanks, said pushrods lying on opposite sides of said common axis and each extending slidably through the opening in the hub of its respective rollback and terminating inwardly of the inner end of its respective knob shank, the free end of each pushrod defining an abutment surface engageable by the hub of the opposite rollback and normally locating said opposite rollback in retractor operating position, spring means contained in each of said knob shanks and urging the rollback therein against the free end of the opposite pushrod, each pushrod, upon rotation of its respective knob shank, being carried in a circular path with the free end thereof sliding over the surface of the hub of the opposite rollback while still maintaining said opposite rollback in retractor operating position, and means contained in each knob shank and accessible for manual operation at the outer face of its knob for moving the pushrod carried thereby axially inwardly to thereby shift the rollback in the opposite knob shank axially outwardly and into engagement with said abutments on the housing to thereby dog the opposite knob shank against operation.

4. The subject matter set forth in claim 3 wherein the openings in the hubs of said rollbacks are equidistant from said common axis whereby said rollbacks may be inserted into either of said knob shanks in reverse relation.
